SHOE DISPLAY DEVICES

Hal M. Fisk, 3764 Shafter Ave., Oakland, Calif.
Filed June 2, 1961, Ser. No. 114,537
1 Claim. (Cl. 211—37)

This invention relates to improvements in devices for attractively displaying shoes in store windows, shoe shops and in the shoe departments of stores, and provides an ornamental, shoe aligning combination, with which a shoe merely needs be hooked from beneath and outwardly and released, the shoe automatically gaining its own most attractive display position.

It is well known that many types of display devices for shoes have been and are being used, usually being supported by the heel on a rack or slanting shelf, which permits showing shoes only in one position unless the display device is turned about its vertical axis.

My invention can be used to display both, a front and a side view of a pair of shoes, and any desired number of different shoes can be displayed on a single display device, since it can be produced in various forms, such as integral with a standard on which shoes can be displayed on one to four sides, and on a peg board on which any number of shoes can be displayed, thus providing a display device.

The objects and advantages of the invention are as follows:

First, to provide a display device on which a shoe need merely be hooked with the shoe automatically aligning and positioning itself in the most artfully displayed position.

Second, to provide a display device as outlined by which shoes may be displayed on any or all sides of a standard or the like, to display both, front and side views of the shoes if desired.

Third, to provide a display device which is adaptable for use in connection with peg board, through the medium of which a great many different shoes can be displayed in a comparatively small space.

In describing the invention reference will be had to the accompanying drawings, in which:

FIG. 1 is a front elevation of a standard with the invention shown as applied to three sides thereof.

FIG. 2 illustrates a modification of the invention as applied to a standard.

FIG. 3 illustrates a modification in which both types of supports are shown as applied to a peg board, and shown full size.

FIG. 4 is an enlarged view of the self-locking peg for mounting on a peg board.

FIG. 5 is a section taken on line 5—5 of FIG. 4.

FIG. 6 is an end view of FIG. 4.

The invention includes a vertical support and an inverted hook having a base attachable to the support, with the hook having a fulcrum provided on its inner end which is spaced from the support, and on which fulcrum the heel portion of a shoe is supportable, with the bottom of the recess forming the hook providing a stop for the top of the heel portion or counter, and with the latter point so located as to cause the heel to rest against the standard or other support, one type of hook being indicated at 10, and another at 11, the type shown at 12 being merely broader and more ornamental, and consisting of a plate-like member having a base cooperative with the vertical support and having a recess formed outwardly and upwardly from the lower end of the base, with the upper end of the base attachable to the vertical support, and the portion below the recess terminating in spaced relation to the support to form a hook to receive the back end of a shoe in the recess, with the bottom of

2

the recess providing a stop for the top edge of the back end of the shoe, and the inner end of the hook providing a fulcrum, all of which depend on two specific points, the fulcrum 13 on the type 10, 14 on the type 11, and 15 on type 12, and each having a stop, indicated at 16 on type 10, 17 on type 11 and 18 on type 12, with the distance from the support 19, 20 or 21 to the point 16, 17 or 18, measured at right angles to the support, being approximately one and a half inches for women's pumps, and which also applies to men's oxfords, while for children's shoes, the distance would be reduced because of the lesser height of the counter portion.

With the inverted hooks so arranged, the top of the counter portion will rest against the points 16, 17 or 18, the inside of the counter resting on the fulcrum 13, 14 or 15, with the back of the shoe and bottom of the heel resting against the support as indicated respectively at 22 and 23.

As illustrated in FIGS. 1 and 2, the invention is formed integral with the standard, while in FIG. 3 the invention can be applied to standards provided with suitable passages, or to any perforated support, such as peg board 21, which also can be formed of ornamental material, such as plastic, glass, or panel board.

FIGS. 3, 4, 5 and 6 illustrate the invention in detail as applicable to any type of support having suitable passages for the anchoring shafts, the shaft having opposed front and rear eccentrics 24 and 25, with intervening cylindrical portion 26, the front eccentric being in a dependent position to provide a front fulcrum, and the rear eccentric 25 being in the opposite position and having an upwardly projecting engaging and locking element 27 to engage the back wall of the support, with the maximum diameter through the rear eccentric and the engaging element being such as to permit passage through the passage 28 in the support, the eccentrics being smaller in diameter than the passage.

Thus the shaft can be inserted through the passage when tilted upwardly, and when released will lock in position through engagement of the engaging element with the back of the support, with the load being applied on the eccentric 24 coupled with reaction through the eccentric 25.

I claim:

45 In a shoe display device including a vertical support, shoe supporting means comprising a plate-like member having a base for attachment to the support, and having a recess formed diagonally upward and outward from the lower end of the base, with the portion below the recess terminating in spaced relation to the support, to form an inverted hook terminating in a fulcrum, with the back end of a shoe insertable in said recess and with the inner end of the recess providing a stop for the top of the back end of the shoe, with the shoe supported by said fulcrum, with the heel portion of the shoe resting against the vertical support the support having a back, and having a passage formed therethrough, means for attaching the shoe supporting means to the support, comprising a shaft projecting rearwardly from the upper end of the base and having front and rear opposed eccentrics with a maximum diameter through the eccentrics to provide for passage through the passage, with the front eccentric in the dependent position, and the rear eccentric having an upward projection to engage the back of the support with

said rear eccentric and upward projection having a maximum diameter to pass through the passage when the shoe supporting means is tilted upwardly, and with the shoe supporting means supported by the front eccentric coupled with reaction through the rear eccentric when a shoe is mounted in the device, thus

providing for installation and removal of shoe supporting means at will.
